UNITED STATES PATENT OFFICE.

GEORGE A. KREUTZER AND KENNETH L. LONG, OF LINCOLN, NEBRASKA; NATALIE C. LONG EXECUTRIX OF SAID KENNETH L. LONG.

COMBINED STOVE AND HUMIDIFIER.

Application filed March 6, 1920, Serial No. 363,895. Renewed August 11, 1923.

To all whom it may concern:

Be it known that we, GEORGE A. KREUTZER and KENNETH L. LONG, citizens of the United States, residing at Lincoln, in the 5 county of Lancaster and State of Nebraska, have invented certain new and useful Improvements in Combined Stoves and Humidifiers, of which the following is a specification.

10 This invention relates to a combined stove and humidifier for internal combustion engines and has as one of its principal objects to provide a device which will supply a heated vapor to the intake of the engine carbureter for thus enhancing the combustibility of the fuel mixture while, at the same time, acting to reduce the formation of 15 carbon in the engine cylinders.

20 A further object of the invention is to provide a device wherein heated air will also be supplied to the intake of the engine carbureter along with the heated vapor.

25 The invention has as a further object to provide a device which will utilize steam generated in the engine radiator and wherein the device will be provided with a drainage valve for preventing flow of water through the device into the engine carbureter.

30 A still further object of the invention is to provide a device wherein the vapor heating chamber employed will be housed within the hood of the stove of the device so that as the steam is drawn into said chamber 35 from the engine radiator, such steam will be heated within the chamber and thence directed off to the carbureter intake.

40 And the invention has as a still further object to provide a device which will be characterized by structural simplicity and which may be readily applied.

45 Other and incidental objects will appear hereinafter.

In the drawings:

45 Figure 1 is a fragmentary side elevation showing our improved device in connection with the engine of a conventional type of motor vehicle, a portion of the hood of the vehicle being broken away.

50 Figure 2 is a vertical section taken on the line 2—2 of Figure 4 looking rearwardly.

Figure 3 is a detail perspective view of the heating chamber of the device, and

55 Figure 4 is a longitudinal section particularly illustrating the mounting of the heat-

ing chamber within the hood of the stove employed and illustrating the connection between the engine radiator and the chamber as well as the connection between the hood of the chamber and the intake of the engine 60 carbureter.

In order that the construction, mounting and operation of our invention may be accurately understood we have, in the drawings shown the device in connection with a 65 conventional type of motor vehicle. The engine of the vehicle is indicated at 10 and lying along one side of the engine is the exhaust manifold 11. The intake manifold is indicated at 12 and connected to this 70 manifold is the engine carbureter 13 having the usual air intake 14. The engine radiator is indicated at 15, this radiator being provided with the usual filler tube 16 closed by a screw cap 17 and, as will be 75 observed, the radiator is formed with a top tank 18.

Coming now more particularly to the subject of the present invention, we employ a jacket or hood 19 having a relatively short 80 back wall 20 and an elongated front wall 21 joined with the back wall by the curved top wall of the hood. Closing the hood at its ends are end walls 22. However, it will be observed that these end walls are 85 notched or cut away to provide shoulders 23 lying in a plane with the lower edge of the back wall and these shoulders are arranged to engage over the exhaust manifold 11, as suggested in Figure 1, for supporting the 90 hood to rest thereon, the inner vertical edges of the end walls below the shoulders seating against the outer side face of the manifold. Secured to the back wall 20 are longitudinally spaced angle brackets 24, the 95 horizontal arms of which are provided with slots 25. The brackets are arranged to align with a pair of bolts securing the cylinder head block of the engine, at the adjacent side of said block, and the slots 25 are adapted to freely receive said bolts so that the horizontal arms of the brackets may be engaged beneath the heads of these bolts for securely connecting the hood to the engine. Formed upon the forward end wall of the 100 hood adjacent its upper end is a collar 26 and formed upon the rear end wall of the hood to align with this collar is a rearwardly projecting collar 27 of somewhat larger diameter than the former collar. Remov-

105

110

ably fitted at one end through the collar 27 to be held therein by a suitable set bolt is a preferably flexible pipe 28 which, at its opposite end, is fitted to the intake 14 of the 5 engine carbureter 13. A stove is thus provided, the hood 19 being adapted to collect heated air rising from the exhaust manifold when this air will, as will be well understood, be drawn off through the pipe 28 to 10 the carbureter.

Removably fitted within the hood 19 is a vapor heating chamber. This chamber is formed with inner and outer side walls 29 and 30 respectively, the lower end portions 15 of which are flat and extend in parallel relation. However, the upper end portions of these walls are curved laterally and merge into the cylindrical dome 31 of the chamber, this dome being offset rearwardly from the 20 lower portion of the chamber. Closing the chamber at its lower end is a bottom wall 32 which, if desired, may carry a clean-out plug 33. Formed on the forward end wall of the chamber axially of the dome 31 is a 25 nipple 34 snugly fitting through the collar 26 of the hood and acting to center the chamber within the upper portion of the hood. At its forward end the chamber abuts the forward end wall of the hood while the 30 rear end of the chamber lies in spaced relation to the rear end wall of the hood to provide an air passage therebetween leading upwardly to the pipe 28. Free flow of heated air will thus be permitted through 35 the hood and through the pipe 28 to the engine carbureter. Since, as previously noted, the dome 31 is offset somewhat with respect to the lower portion of the chamber, the outer side wall 30 of the chamber 40 seats flat against the front side wall 21 of the hood and fitted through the latter wall are spaced cap bolts or other suitable fastenings 35 threaded into sockets 36 formed on the outer side wall of the chamber. 45 The chamber will thus be rigidly supported within the hood and, as will be noted upon reference to Figure 2, the lower portion of the chamber is of a width corresponding to the width of the reduced portions of 50 the end walls 22 of the hood so that the lower portion of the chamber thus lies between the front side wall of the hood and the exhaust manifold 11, resting against the manifold while the upper portion of the 55 chamber extends upwardly over the manifold in such manner that the dome 31 is disposed directly above the manifold. The dome will thus be directly subjected to the heat rising from the manifold. Further, in 60 this connection it is to be observed that a dead air space is formed within the upper portion of the hood about the dome so that the heat rising from the exhaust manifold will be held or detained around the dome for 65 heating the dome in maximum degree.

Freely fitted at one end through the nipple 34 of the chamber is a vapor pipe 37 received through a gland 38 upon the nipple, this gland, of course, forming a tight joint between the pipe and chamber. The pipe 70 is preferably flexible and the opposite end portion thereof is led through a suitable gland 39 upon the back wall of the top tank 18 of the radiator and is carried upwardly 75 within the radiator to terminate within the filler tube 16. If desired, the upper end portion of the pipe may, as suggested in Figure 4, be suitably secured to the upstanding upper end portion of the overflow pipe of the radiator. The pipe 37 is thus arranged to conduct steam rising into the filler tube 16 of the radiator into the dome 31 of the heating chamber and since, as sometimes happens, the level of the water 80 in the radiator will rise into the filler tube, the pipe will, when this occurs, also conduct a supply of water into the chamber. The forward end wall of the chamber is provided with a substantially V-shaped depression 40 and the lower inclined wall of this depression is formed with an overflow opening 41 lying in a plane near the bottom wall of the chamber. Normally closing said opening so that the chamber is thus rendered air tight, is a flap valve 42. As particularly 95 shown in Figure 3, the valve is forked at its upper end to provide spaced hinge lugs which mate with a hinge lug formed at the crotch of the inclined walls of the depression 40, the several lugs receiving a suitable 100 pivot pin so that the valve thus normally gravitates to closed position. However, when the water in the lower portion of the chamber reaches the level of the opening 41, the water will seep out through said 105 opening beneath the valve so that flooding of the chamber will thus be automatically prevented, the level of water in the chamber being maintained relatively constant. Formed on the rear end wall of the chamber 110 in alignment with the nipple 34 is a collar 43 and freely fitted at one end through this collar is a preferably flexible vapor discharge pipe 44 which may be held within the collar by a suitable set bolt. The pipe 44 is led downwardly within the pipe 28 and at its lower end terminates, as best seen in dotted lines in Figure 4, in spaced relation to the adjacent end of the air pipe to 115 provide an ejector for the chamber.

As will now be readily appreciated in view of the previous description, when the vehicle engine is running, a supply of heated air will be drawn into the carbureter through the pipe 28. At the same time, suction set 120 up in the carbureter will act to create a partial vacuum in the vapor heating chamber so that vapor from the engine radiator will be drawn into this chamber through the pipe 37. The vapor so entering the 125

chamber will, of course, emerge into the heating dome 31 and since this dome will, for the reasons previously pointed out, be heated the hottest of any part of the chamber, the vapor will be heated within the chamber in its passage therethrough to the pipe 44, the vapor being drawn off through this pipe and finally discharged into the intake of the carbureter. In thus heating the vapors drawn from the radiator, condensation within the heating chamber will be reduced to a minimum while the high temperature of the vapor will assist in the vaporization of the liquid fuel in the carbureter as well as also tend to promote a homogeneous union of the vapor with the fuel mixture. In supplying heated air to the carbureter, vaporization of the liquid fuel will, as is well known, be enhanced and in constantly supplying moisture along with the heated air supply, the combustibility of the fuel mixture will also be increased. Since the lower portion of the heating chamber lies directly against the exhaust manifold, water collecting within the lower portion of the chamber will be heated in such degree as to give off a vapor therefrom and, of course, this vapor will rise into the heating dome of the chamber to be thence drawn off through the pipe 44. Owing to the small body of water which will be contained within the chamber, this small body will, when the vehicle engine is first started, begin to give off a vapor before the generation of steam in the engine radiator. Accordingly, the heating chamber will, at a time soon after the engine is started, function independently of the main steam supply from the engine radiator for supplying moisture to the carbureter and keeping down the formation of carbon in the engine cylinders when the engine is started and until the steam begins to flow from the radiator into the heating chamber. We accordingly provide a particularly effective construction for the purpose set forth and, as will be seen, a device which may be readily employed in connection with the engine of substantially any conventional type of motor vehicle.

Having thus described the invention, what is claimed as new is:

1. A device of the character described comprising, a heating chamber having a vapor inlet and a vapor outlet disposed adjacent the top thereof, a hood forming a jacket over the top and one side of said heating chamber and having an opening alining with the vapor outlet, a heated air conduit connected with said hood opening, and a water vapor conduit extending

through said heated air conduit leading from the vapor outlet to the carbureter of an engine.

2. A device of the character described comprising, a heating chamber having a vapor inlet and a vapor outlet disposed adjacent the top thereof, a gravity closed valve approximate the bottom of said chamber to remove excess liquid accumulation therefrom, a hood forming a jacket over the top and one side of said heating chamber and having an opening alining with the water vapor outlet, a heated air conduit connected with said hood opening, and a water vapor conduit extending through said heated air conduit and connected with the vapor outlet.

3. A device of the character described comprising a hood having alining openings, a heating chamber enclosed by said hood and also having alining openings, nipples on each of said openings, one of said nipples engaging one of the hood openings to support said chamber with relation to the hood, and conduits connected to the nipples.

4. In combination with an internal combustion engine, having an exhaust manifold, a carbureter and a radiator with a steam receptacle; of an enclosed chamber having one side contacting with said manifold, a conduit between said steam receptacle and said chamber, a hood open at the bottom and seated upon the manifold and enclosing said chamber, means securing the chamber to said hood, a pipe connection between said hood and said carbureter and a discharge pipe from said chamber for delivering steam through said pipe connection to the carbureter.

5. In combination with an internal combustion engine, having an exhaust manifold, a carbureter and a radiator with a steam receptacle; of an enclosed chamber having one side contacting with said manifold, a conduit between said steam receptacle and said chamber, a hood open at the bottom and seated upon the manifold and enclosing said chamber, means securing the chamber to said hood, a pipe connection between said hood and said carbureter and a discharge pipe from said chamber for delivering steam through said pipe connection to the carbureter, said chamber having an inclined wall provided with a port and an exteriorly mounted, gravity actuated valve for closing said port.

In testimony whereof we affix our signatures.

GEORGE A. KREUTZER. [L.S.]
KENNETH L. LONG. [L.S.]
